UNITED STATES PATENT OFFICE.

JAMES G. DUNN, OF MIMICO, ONTARIO, CANADA.

LOCOMOTIVE VALVE GEAR.

Application filed February 24, 1925. Serial No. 11,263.

This invention relates to new and useful improvements in valve gears for locomotives and other types of steam engines and is particularly related to valve gears of the well known Walschaert type, and the object of the invention is to provide a simple and highly efficient arrangement of valve control mechanism which will allow a longer travel without objectionable angular movement to any of the working parts when compared with valves of the Walschaert type in use on locomotives at the present time.

Another object is to provide a device of the class stated in which the valve movement will be always in advance of and greater than the radius rod movement.

In my invention the construction, briefly described, is very similar to the standard Walschaert gear in that I employ the turn crank principle for operating the links, the lap and lead movement being operated from the cross-head through a connecting member known as the transmission lever or lap and lead lever. In my construction this transmission lever is connected to the cross-head by a union link and crosshead arm. The transmission lever extends upwardly and is forked just below the valve stem which is positioned below the transmission lever trunnions which are placed in line with the reversing link trunnion. The transmission lever extends a short distance above its trunnions and pivotally mounted between the forked portions and depending from the upper end thereof is the combination lever which is connected to the front end of the radius rod at a point radially coincident with the centre of the transmission lever trunnions. The end of the combination lever is connected to the valve stem by means of the valve stem link.

This construction of transmission lever and combination lever increases the valve travel from 35% to 40% without increasing the swing of the link when compared with the standard Walschaert gear.

In the drawings:

Figure 1 is a side elevation of my improved valve mechanism applied to a locomotive.

Figure 2 is an end elevation showing the construction of the transmission lever and combination lever.

Referring more particularly to the drawings which show part of the side of a locomotive, 11 designates the locomotive frame,

12 the main cylinders and 13 the valve or steam chest. The piston rod 14 is provided with a crosshead 15 which is pivotally connected to a crank 16 on the driving wheel 17 by means of the connecting rod 18. The eccentric crank 19 is located 90° behind or in front of the main crank and is pivotally connected to one end 20 of the reversing link 21 by means of the eccentric rod 22. The reversing link is pivotally attached to the frame by means of the bracket 23^a in such a manner that the link block 23 which is slidably mounted in the slot 22^a formed in the reversing link can be moved an even distance on each side of the centre of the bracket. The link block may be raised or lowered by means of the reversing lever 24 which is connected to the block by means of the links 25 the rocker arm 26 and the link 35. Depending from the crosshead is the crosshead arm 27 which is connected to the lower end 28 of the transmission lever 29 by means of the link 30. Said lever 29 is pivotally mounted in trunnions 31 rotatably mounted in brackets 32 secured to the frame. The centre of the trunnions are in line with the centre of the link pivot and are spaced from one another a distance equal to the length of the radius rod 33 so that when the link block is in the centre position there is no movement in the radius rod and therefore no movement in the valve stem 34 which is connected in the manner herein-after described. The foregoing description has reference to the parts used in the standard Walschaert gear and the following description relates to the portion of the valve control mechanism in which my improved construction lies. The transmission link is 95 forked just below the level of the valve stem, said forked portion extending above the trunnions 31 where the upper ends 36 of the forked portion may be brought together as shown for illustrative purposes. 100 Pivots suspended on a pin 37 passing through the ends 36 and between the fork is the combination lever 38, the lower end of which is connected to the valve stem link 39 which is connected to the valve stem. 105 The connection between the combination lever and the valve stem is positioned preferably a short distance below the centre of the trunnions 31. The end 40 of the radius rod is connected to the combination lever 110 at a point radially coincident with the centre of the trunnions 31 of the transmission

lever. Modifications may be made without departing from the spirit of the invention. In operation the back and forth movement of the bottom of the transmission link with the crosshead and piston imparts a radial movement to the top of the transmission lever (said radial movement being about the trunnions 31) and, consequently, an indirect movement to the top of the inverted combination lever which, using the radius rod as a fulcrum, imparts to the valve rod and, therefore, to the valve a movement in the same direction as the piston, said movement being equal to the lap plus lead. The radius rod movement from the reversing link acting on the combination lever at a point above the valve stem, imparts to the valve a movement always in advance and greater than the radius rod movement itself, because at the same time the top connection of the combination lever acts as a fulcrum and permits the lower connection to swing between the forked end of the transmission link, imparting to the valve a travel in the opposite direction to the piston and crosshead. The combination lever being inverted, and the radius rod being connected to the combination lever above the valve stem connection and between the transmission lever fulcrum points, enables this gear to increase the valve travel without increasing the swing of the reversing link.

Having thus described my invention, what I claim is:—

35 1. In a valve gear for locomotives and other types of steam engines, an inverted combination lever connected at its lower end to the valve stem, a radius rod connected to the combination lever above the valve stem connection, pivotally mounted means operated by the movement of the piston and connected to the upper end of the combination lever adapted to impart to the valve a predetermined movement in the same direction as the piston, using the radius rod connection as a pivot, and means operable by the piston for moving the radius rod.

50 2. In a valve gear for a steam engine, a lap and lead lever pivotally mounted on the engine frame, means for connecting the lower end of the lever to the engine crosshead, a combination lever depending from the other end of the lap and lead lever and a valve stem connected to the combination lever at a point below the lap and lead lever pivot.

55 3. In a valve gear for a steam engine, a fork ended lap and lead lever pivotally mounted on trunnions rotatably attached to the engine frame, a link connection between

the lower end of the said lever and the crosshead of the engine, a combination lever depending from the other end of the lap and lead lever and between the arms of the fork, a valve stem connected to the combination lever at a point below the level of said trunnions, a radius rod attached to the combination lever at a point in line with the trunnions, and means operable by the engine piston for transmitting motion to the radius rod.

4. In a valve gear for a steam engine a fork ended lap and lead lever pivotally mounted on trunnions secured to the engine frame, a link attachment between the lower end of said lever and the crosshead of the engine, a combination lever pivotally attached to the upper end of the lap and lead lever and depending between the arms of the forked end of same, a valve stem connected to the combination lever at a point below the level of the trunnions, a radius rod connected at one end to the combination lever at a point radially coincident with the trunnion centres, a slotted reversing link pivotally attached to the frame, a link block slidably mounted in the reversing link and pivotally attached to the other end of the radius rod, means operable by the engine piston for operating the reversing link and means for moving the link block to any desired position in the slot of the reversing link.

5. In a valve gear for locomotives having cylinder valve chests, pistons, crossheads, driving wheels and connecting rods between the driving wheels and crossheads, a fork ended lap and lead lever pivotally mounted on trunnions secured to the engine frame, said fork end being adapted to extend above the trunnions, a link connection between the crosshead and the lower end of the lap and lead lever, a combination lever rotatably suspended from the other end of the lap and lead lever and between the arms of the forked end thereof, a valve stem connected by link to the combination lever below the level of the trunnions, a slotted reversing link pivotally mounted on the frame, an eccentric rod connected to the driving wheel and the reversing link, a link block slidably mounted in the slot, a radius rod having one end connected to the link block and the other end to the combination lever at a point radially coincident with the trunnions, and means for shifting the link block to any desired position in the slot.

In witness whereof, I have hereunto set my hand.

JAMES G. DUNN.
